mington, Del., a corporation of DelawareNo Drawing. Application August 18, 1950,
Serial No. 180,313

6 Claims. (Cl. 52—11)

1

This invention relates to explosive compositions of the type of the nitroglycerin dynamites and more particularly to gelatinized explosives of improved properties.

This application is a continuation-in-part of my co-pending United States application, Serial Number 655,889, filed March 20, 1946, now abandoned.

Commercial dynamites comprise essentially nitroglycerin or its equivalent of liquid explosive nitric esters, a carbonaceous combustible absorbent for the liquid explosive, and one or more inorganic oxidizing agents, particularly sodium nitrate and ammonium nitrate. One of the important types of such dynamites is the class of gelatin dynamites, in which the nitroglycerin is partially gelatinized to a thickened viscous fluid by solution therein of a predetermined quantity of nitrocellulose of suitable characteristics. This liquid is then incorporated by thorough mixing with the solid ingredients, comprising absorbents and oxidizing agent. The completed blend is of a solid plastic consistency and is extruded into the cylindrical paper shell that is to serve as the container for the explosive. In the case of the so-called ammonia gelatins, nitroglycerin is replaced by ammonium nitrate as the effective explosive ingredient to as great an extent as is consistent with retaining sufficient plasticity to allow satisfactory working or extruding properties, and also field properties. The amount of this replacement is often limited by the plasticity requirements to a quantity less than is desired.

An object of the present invention is an explosive composition comprising a liquid explosive nitric ester and a solid inorganic oxidizing ingredient, said composition retaining superior working properties even with a reduced content of liquid explosive. A further object is a gelatinized nitroglycerin explosive of the above nature. A still further object is a gelatinized nitroglycerin dynamite possessing superior working properties because of the inclusion in the composition of an ingredient that promotes the plasticity of the mixture even with reduced content of nitroglycerin. A further object is a method of producing explosives of the improved properties described. Additional objects will be disclosed as the invention is described more at length hereinafter.

I have found that the reason the replacement of the liquid nitric ester with the water soluble inorganic salts is limited is that the salts are essentially not wetted by the liquid nitric ester, and that, therefore, a homogeneous plastic mass is not produced, even with considerable mixing

2

action. A quantity of liquid greater than desired is thus necessary so that the mixture may have the required working properties and field characteristics. I have further found that the above mentioned deficiency can be overcome by incorporating a small quantity of a wetting and emulsifying agent into the explosive mixture during the mixing step. The inclusion of this small quantity of a surface active agent causes a reduction in the interfacial tensions between the water-soluble salts and the liquid nitric ester, and permits the formation of a homogeneous mixture having the required plasticity even when the liquid nitric ester is present in proportions appreciably less than heretofore believed possible.

The reduction of the interfacial tensions between the liquid nitric ester and the inorganic salt is the crucial point in this invention, and may be brought about by any surface active agent. Surface active agents, as used in this description, are compounds possessing a non-polar group of at least eight carbon atoms, and a polar group such as hydroxy, alkyl carboxylate, amino carboxylate, sulfonate, sulfate, acid phosphate ester, amino, and quaternary ammonium radicals. The compounds possessing the desired properties are esters and amides of long chain aliphatic carboxylic acids, soaps of organic bases and of alkali metals, unsubstituted aliphatic monohydric alcohols, organic sulfonates, organic sulfate esters, long chain aliphatic amines and their salts, quaternary ammonium compounds, and esters of long chain alkyl phosphates.

The following examples will serve as specific embodiments of explosive compositions prepared in accordance with the invention. It will be understood, of course, that these are by way of illustration only and are not to be considered as limiting in any way.

40

Example 1

A mixing of a gelatin dynamite of the following final composition was made, in an amount of 6,000 grams:

	Per cent
Nitroglycerin	21.0
Nitrocotton	0.5
Ammonium nitrate	14.1
Sodium nitrate	49.1
Carbonaceous combustible material	9.0
Sulfur	6.0
Chalk	0.3
	100.0

55 In making the mixing, the nitroglycerin was

introduced into the mixing bowl, the temperature maintained at about 120° F. and the nitrocotton added. An amount of triethanolamine oleate was included also, in an amount equal to 0.1% of the total composition. The mixture was agitated for about five minutes until the explosive solution had become viscous, and the blended solid ingredients were then added. After further mixing for about ten minutes, the plastic mass was removed from the bowl and extruded into the open ends of paper shells of 1 1/4 in. diameter and 8 in. length, closed at the further end. After filling, the open ends of the shells were closed by folding over.

The gelatinized explosive extruded readily whereas a similar composition, to which no triethanolamine oleate had been added, could not be extruded. In analogous compositions, in which the nitroglycerin content had been lowered to as low as 19%, good extrudability was obtained when the added material was present. The gelatin dynamite containing the added triethanolamine oleate showed satisfactory stability on continued storage at an elevated temperature.

Example 2

An ammonia gelatin dynamite on a similar formula was made, except that the added wetting agent in the same amount was laurylamine hydrochloride, the nitroglycerin content being 23%, and other slight changes being made. The composition extruded very satisfactorily, while a similar composition containing no added promoter could not be extruded.

Example 3

An ammonia gelatin dynamite was made having a nitroglycerin content of 23% and generally similar in composition to that of Example 1. A surface active agent was introduced with the nitroglycerin comprising sorbitan monolaurate in the amount of 0.5%. Whereas a similar composition containing no added promoting agent could not be extruded, the composition of the present example extruded without difficulty.

Example 4

A similar ammonia gelatin was made of the general composition of Example 1, and containing 23% nitroglycerin, to which was added 0.5% by weight of the entire composition of a salt of a long chain fatty acid amide. The gelatinized composition extruded very satisfactorily.

Example 5

An ammonia gelatin dynamite was made of the general formula of Example 1, containing 23% nitroglycerin, to which an amount of the diethyl ester of sodium sulfosuccinic acid had been added, in an amount of 0.5% of the composition. The explosive extruded satisfactorily, though a similar composition without the added plasticity promoter could not be extruded.

Example 6

A similar composition, in which 0.5% had been added to the nitroglycerin of a sulfate of a long chain aliphatic alcohol, possessed excellent extrusion properties.

Example 7

An ammonia gelatin was prepared containing lauryl pyridinium chloride, a quaternary ammonium salt, in the amount of 0.5%, 23% nitroglycerin being present. Excellent extrusion properties were obtained.

Example 8

5 A similar mixing was made, using 23% nitroglycerin, to which had been added 0.5% of a substituted amide of an alkyl phosphate (12 carbon atoms). The gelatinized composition extruded very satisfactorily.

Example 9

10 A gelatin mixing was made of the following compositions:

	Per cent
Nitroglycerin	21.0
Nitrocotton	0.5
15 Ammonium nitrate	12.9
Sodium nitrate	49.8
Carbonaceous combustible material	9.0
Sulfur	6.5
Chalk	0.3

20 Laurylamine in an amount of 0.5% of the entire composition was introduced into the nitroglycerin prior to mixing. The gelatinized composition possessed satisfactory extrusion properties, whereas a similar composition without the added plasticity promoter could not be extruded.

Example 10

30 A similar composition was made except that, instead of the laurylamine, triethanolamine and sodium stearate in amounts of 0.25% each were added to the nitroglycerin. The finished composition possessed excellent extrusion properties.

Example 11

35 A semigelatin type of composition was prepared, i. e., one containing a reduced amount of liquid explosive and gelatinizing agent, sufficient to have a binding effect and to promote water resistance but insufficient to allow the extrusion 40 of the explosive. The composition was as follows:

	Per cent
Nitroglycerin	14.0
Nitrocotton	0.3
45 Ammonium nitrate	69.0
Sodium nitrate	9.6
Carbonaceous combustible material	5.8
Sulfur	1.0
Chalk	0.3

50 Laurylamine hydrochloride in the amount of 0.5% of the entire composition was introduced into the nitroglycerin prior to mixing. The finished composition possessed superior properties 55 with respect to cohesiveness and plasticity.

As is brought out in the foregoing examples, the surface active agent included in the explosive compositions is added to the nitroglycerin and becomes dissolved or suspended therein. Desirably we use the agent in an amount not greater than 0.5% of the composition and not less than 0.01%. A suitable amount is between 0.05% and 0.3%. Because of the small quantity used, little difficulty is met in the case of any of the desired materials in obtaining solution in the liquid explosive.

The function of the added wetting and emulsifying agent is to increase the plasticity of gelatinous explosives containing nitroglycerin or other liquid explosive nitric ester. This is particularly important in the case of gelatin dynamites containing relatively large amounts of solid inorganic nitrates, i. e., sodium nitrate or ammonium nitrate, or both. In such explosives, it is necessary to have sufficient nitroglycerin present to

allow ready extrusion of the plastic mixture through an orifice into the paper shells to be filled, and to maintain plasticity for use in the field. This requirement places an undesirably high limit on the minimum content of liquid explosive that must be used. The presence of the surface active agents, added in accordance with the present invention, imparts a wetting effect to the liquid explosive so that equivalent ease of extrusion results with markedly lower liquid content. For example, with a gelatinous explosive normally containing 29% nitroglycerin, this content was reduced to as low as 19% by addition of a suitable plasticity promoting agent, without undesirable effect on the extrudability, or on the explosive properties.

A considerable number of agents are adapted for effective use in accordance with the present invention. The materials proposed will include, for example, esters and amides of aliphatic carboxylic acids such as the coconut oil acids, the esters being represented by materials such as long chain fatty acid esters of hexitol anhydrides, i. e. of sorbitans, mannitant, etc., while the amides may comprise salts of fatty acid amides such as trimethyl-aminoethyloleylamide sulfate or diethylaminoethyloleylamide acetate. A particularly preferred class of compounds comprises the organic soaps, for example triethanolamine oleate, the laurate and stearate of triethanolamine, etc. The soluble soaps of the alkali metals may likewise be used, as sodium and potassium stearates. An additional desirable group of compounds comprises the organic sulfonates, for example alkyl sulfonates, of which the diethyl ester of sodium sulfosuccinic acid is an example; aryl sulfonates, e. g. the sodium salt of an aryl alkyl polyether sulfonate; and a sodium petroleum sulfonate. A further important class comprises the organic sulfate esters, such as the sodium salts of sulfates of the coconut oil acids, for example sodium glyceryl monolaurate sulfate. Long chain aliphatic amines and their salts have proved effective, for example laurylamine and laurylamine hydrochloride. Quaternary ammonium compounds are likewise effective, for example lauryl pyridinium chloride. A further group of satisfactory compounds comprises amides and esters of long chain alkyl phosphates, the amides being represented by substituted amides of alkyl phosphates, the alkyl group having between 12 and 18 carbon atoms. As an example of suitable esters of this group, I may cite the mixed mono- and di-lauryl acid phosphates, or mixture of such acid phosphates of the various coconut oil acids.

As has been stated, the invention will find its principal application in gelatinized explosives containing liquid explosive nitric esters in the presence of a considerable amount of solid ingredients, particularly inorganic oxidizing agents. While nitroglycerin is the outstanding liquid nitric ester underlying dynamite compositions, the invention is applicable where nitroglycols or other liquid ester equivalents have replaced nitroglycerin, including solutions of various freezing point depressants in nitroglycerin. Carbonaceous combustible absorbent materials will almost invariably be present for absorption of the liquid explosive. The inorganic oxidizing ingredients will mainly comprise ammonium nitrate and sodium nitrate, but such other agents

as ammonium and potassium perchlorates, potassium nitrate, etc. may be used. It will be effective also with the so-called semigelatins where a considerably reduced amount of liquid explosive is present, where extrusion is not involved but better plasticity of the compositions is desired.

The invention has been described at length in the foregoing. It will be understood, however, that many variations may be introduced with respect to details of compositions, compositions of the surface active agents, and methods of application, without departure from the spirit of the invention. I intend to be limited only by the following claims:

I claim:

1. A gelatinous explosive dynamite composition comprising an inorganic oxidizing agent, from 19 to 29% of a liquid explosive nitric ester, a gelatinizing agent therefor, and from 0.01 to 0.5% of a surface active agent having a non-polar group of more than eight carbon atoms, and at least one polar group from the class consisting of hydroxy, alkyl carboxylate, amino carboxylate, sulfonate, sulfate, acid phosphate ester, amino, and quaternary ammonium radicals, said compound being taken from the group consisting of esters and amides of long chain aliphatic carboxylic acids, soaps of organic bases and of the alkali metals, unsubstituted aliphatic monohydric alcohols, organic sulfonates, organic sulfate esters, long chain aliphatic amines and their salts, quaternary ammonium compounds, and esters of long chain alkyl phosphates.
2. The explosive composition of claim 1, in which the surface active organic compound is a soap of an ethanolamine.
3. The explosive composition of claim 1 in which the surface active organic compound is triethanolamine oleate.
4. The explosive composition of claim 1, in which the surface active organic compound is a laurylamine salt.
5. The explosive composition of claim 1, in which the surface active organic compound is an alkyl sulfonate.
6. An explosive composition as claimed in claim 1, wherein the inorganic oxidizing agent is ammonium nitrate.
